UNITED STATES PATENT OFFICE.

PHILIP WUEST, JR., OF WOODBURY, NEW JERSEY, ASSIGNOR TO THE BLASIUS PIANO COMPANY, OF WOODBURY, NEW JERSEY, A CORPORATION OF NEW JERSEY.

MUSICAL INSTRUMENT.

No. 913,867.

Specification of Letters Patent. Patented March 2, 1909.

Application filed July 1, 1908. Serial No. 441,354.

To all whom it may concern:

Be it known that I, PHILIP WUEST, Jr., a citizen of the United States, residing at Woodbury, county of Gloucester, and State 5 of New Jersey, have invented a new and useful Improvement in Musical Instruments, of which the following is a full, clear, and exact description, reference being had to the accompanying drawings, which form a part of 10 this specification.

My invention relates to automatic playing mechanism, and particularly to the valve mechanism which controls the operation of the pneumatic bellows motor for operating 15 the keys.

Specifically, it relates, in this combination, to a form of construction of valve-seat, which will prevent any leakage and at the same time enable the valve to be properly 20 guided to its seat.

In this class of instruments, the valve-box is provided with two openings, in each of which is a valve-seat. These openings are in communication with the pneumatic 25 bellows, and connect the bellows with the atmosphere, so that the bellows is inflated, or connected with an exhaust in the inflated condition of the bellows, which causes it to be inflated. Two valves upon a common 30 stem control these openings. The movement of the valve is controlled by means of a diaphragm in communication with the air in the instrument. When air is admitted through perforations in the paper to a point 35 below the diaphragm, the valve-stem is lifted, which seats the corresponding valve upon the inlet port seat to the bellows and lifts the valve from the seat in the opening to the exhaust, thus deflating the bellows, 40 causing the key to be struck. There is provided a small opening from the air inlet to the exhaust, so that when the solid paper 45 covers the inlet, the air below the diaphragm exhausts and the atmospheric pressure causes a reverse movement of the valves, seating one valve in the exhaust seat, and moving the other valve from the seat having the opening leading to the atmosphere and the bellows is again inflated. It is essential, 50 if possible, that these seats and their relation to the valves shall be such that when the valve is seated upon its corresponding seat, there shall be no leakage of air. Further, it is very essential that the valve should 55 be guided correctly to its corresponding

seat and that there shall be no cutting of the valve by the seat. Where flat disks, having a central orifice, are used, there are quite a number of difficulties encountered. Among these are the following: The securing of the 60 seat in place is likely to make the face of the seat irregular; that is, a tendency to buckle, and further, the mouth of the orifice being an edge, is likely to cut the valve. Even if the central portion of the disk be counter- 65 sunk, this will not prevent the remaining portion of the disk, where it is connected to the box, buckling, thereby tending to produce an irregular surface, and further, the cutting of the valve is not obviated. 70

In my improved construction the valve-seat consists of a disk having a central orifice. Around its outer surface, this disk is flanged, said flange projecting upwardly from the side opposite to that upon which 75 the valve seats. In like manner, the wall of the central orifice is flanged. Between these two flanges is arranged a sector which makes a snug fit. This sector is provided with an offset portion provided with a bearing for 80 the valve-stem. The valve disk or seat is provided with orifices for the reception of screws to secure it to the cover board. In like manner, the sector is provided with orifices which are caused to coincide with the 85 orifices in the valve-seat. By this arrangement, the valve disk or seat is so stiffened that the danger of irregularity of its face is avoided, thus a seat is obtained in which there is no leakage. This enables the range 90 of playing keys or notes to be largely increased. Further, there is no danger of cutting the valve. Finally the valve bearing is arranged true with respect to the seat and, when worn, may be removed and replaced without discarding the disk. 95

I will now describe the embodiment of my invention illustrated in the accompanying drawings, and then point out the invention in the claims.

In the drawings: Figure 1 is a sectional view through valve-box and bellows. Fig. 2 is a perspective view of valve seat. Fig. 3 is a perspective view of valve stem guide. Fig. 4 is a plan view showing valve stem 105 guide centered on the valve seat disk.

The valve-box has two chambers, *a* and *b*. The chamber *a* communicates with an exhaust and the chamber *b* with the pneumatic *c*, through passage *d*. 110

e is the bottom board of the valve-box and *f* the top board. In the top board is the chamber *b*.

g is a passage, whose connection with the air bellows of the instrument is controlled by the roller and perforated paper, not shown. This passage *g* terminates below the diaphragm *h*. There is also a small opening *i* from passage *g* to chamber *a*. Between chambers *a* and *b* is an opening *j*, and in the upper portion of chamber *b* an opening *q* to atmosphere. In each of these openings is secured a disk *l* having a central orifice *m*. Around the outer edge of the disk is the flange *n*. Integral therewith and around the orifice *m* is a corresponding flange *z*.

o is the valve-stem having the valves *p* thereon, one adapted to seat on one face of the disk in opening *j* the other on one face of the disk in opening *q*. These valves are of soft material and of the ordinary construction. The stem of these valves is operated by the diaphragm *h*. The disk is provided with orifices 10 for securing the disk in position. As may be seen one face of this disk forms a flat seat for the valve while the other face is provided with flanges projecting upward around its orifice and around its outer edge.

When air is admitted to passage *g*, the diaphragm is lifted, lifting the valve-stem and opening connection between chambers *a* and *b*, and hence connecting passage *d* with the exhaust, and the bellows motor *c* deflates, operating the corresponding key in the well known manner. When air is cut off from passage *g*, the air therein exhausts through passage *i* and the diaphragm is relaxed, the valve-stem dropping, closing the opening between chambers *a* and *b*, and opening the opening between chamber *b* and the atmosphere. As the previous deflation of the bellows motor *c* has caused a partial vacuum, the passage *d* being now connected with air, the air will pass in, inflating the bellows motor *c*. Between the flanges *n* and *z* is placed the sector *r* having integral therewith the projection or offset portion *s*, provided with an opening *t*, through which passes the valve-stem and which acts as a guide to the valve-stem to guide the valve true to its seat. It is evident that the nearer the approach to a tight closure between the valve and seat, the nearer is the approach to elimination of leakage.

By my arrangement there is no buckling or irregularity in the surface of the disk, the

flanges preventing this; further, the flanges extending away from the seating surface of the disk, no cutting or abrading edge is presented to the valve. Finally, the valve-stem guiding arrangement is placed, with certainty, concentric and in proper position, and, if the valve-stem bearing wears, may readily be replaced. Thus, by having a true surfaced seat, the valve can equally seat at all points. The disk having no cutting edges, the valve remains true. By having a valve-stem guiding surface which starts true and can readily be replaced, the valves are carried true to the seat.

Having now fully described my invention, what I claim and desire to protect by Letters Patent is:—

1. In a piano player, the combination with a pneumatic bellows motor and its controlling valves, of centrally orificed disks, one face of each disk forming a flat seat for its corresponding valve, flanges projecting upward from the opposite face of each disk around its orifice and around its outer edge, each disk having openings through said disk for securing said disk in position.

2. In a piano player, the combination with a pneumatic bellows motor and its controlling valves, of seats for said valves, comprising a disk having a central orifice, the outer and inner edges of said disk being bent to form flanges, and a sector inserted between said flanges and concentric therewith, said sector having an offset portion having a bearing for the valve-stem.

3. For a piano player, a centrally orificed disk one face of which forms a flat seat for a valve, flanges projecting upward from the opposite face of said disk around its orifice and around its outer edge, and openings through said disk for securing said disk in position.

4. A valve-seat and valve-stem guide for a piano player, comprising a disk having a central orifice, the outer and inner edges of said disk being bent to form flanges around said disk, and a separate sector inserted between said flanges and concentric therewith, said sector having an offset portion having a bearing adapted for the valve-stem.

In testimony of which invention, I have hereunto set my hand, at Woodbury, on this 25th day of June, 1908.

PHILIP WUEST, Jr.
